SNARE DRUM STRAINER

Josephus B. Thompson, Covington, Ohio, assignor to
Joseph Rogers, Inc., Cleveland, Ohio

Filed Oct. 26, 1959, Ser. No. 58,051

Term of patent 14 years

(Cl. D56—1)

Fig. 1

Fig. 2

Fig. 3

Fig. 4

I claim:

The ornamental design for a snare drum strainer, substantially as shown.
